UNITED STATES PATENT OFFICE.

JOHN STRAUB, OF ASHLEY, NORTH DAKOTA.

TOOL FOR CUTTING BANANAS FROM BUNCHES THEREOF.

Application filed February 20, 1923. Serial No. 620,242.

To all whom it may concern:

Be it known that I, JOHN STRAUB, a citizen of the United States, residing at Ashley, in the county of McIntosh and State of 5 North Dakota, have invented certain new and useful Improvements in Tools for Cutting Bananas from Bunches Thereof, of which the following is a specification.

This invention has reference to tools for 10 cutting bananas from the bunch thereof, and its object is to provide a device by means by which bananas may be severed, one at a time, from the bunch thereof and deposited in a sack to be subsequently 15 wrapped and delivered to a customer without the handling of the bananas on the part of the salesman, so that no contamination of the bananas can take place during the interim between hanging up the bunch 20 of bananas and the delivering of the chosen number to the customer.

In accordance with the invention, the bunch of bananas is hung up from an elevated point and is then subjected to a severing blade capable of operating upon a single banana at a time to drop the severed banana in a bag or sack, collecting the severed bananas until the desired quantity thereof is obtained, after which the bananas enclosed 25 in a sack are removed from the device and delivered to the customer without the necessity of handling the bananas by the person 30 selling them.

The instrument comprises a box or enclosure having a readily opened side door and a constricted chute into which the individual bananas are directed to be treated by a severing knife or blade and allowed to 35 gravitate into a sack or container.

40 There is provided in conjunction with the box or receptacle into which the individual bananas as severed are directed, a handling or directing hook which the operator may grasp so as to position the bunch of bananas with the chosen one to be severed 45 in position to drop into the box or receptacle after being severed and to choose the individual bananas to be so treated.

The box or receptacle to contain the 50 severed bananas is also arranged to contain a sack, say a paper sack, into which the severed bananas gravitate, and the box or receptacle is provided with a door which may be opened when it is desired to 55 move the chosen number of severed bananas for delivery to the customer.

The invention will be best understood from a consideration of the following detailed description taken in connection with the accompanying drawings, forming part 60 of this specification, with the understanding that the invention is not confined to any strict conformity with the showing of the drawings, but may be changed and modified so long as such changes and modifications mark no material departure from the salient features of the invention as expressed in the appended claims.

In the drawings:

Figure 1 is an elevation of the box or 70 container together with the manipulating hook forming the complete apparatus.

Fig. 2 is a vertical central section of the receiving and containing box.

Fig. 3 is a vertical section through the 75 box with the manipulating handle omitted.

Fig. 4 is a perspective view of the box complete.

Referring to the drawings and particularly to Figs. 1 to 4 inclusive, there is shown 80 a box 1, which may be of cubical or similar shape and made of metal or other material, say of sheet metal, to conserve weight.

The box may be effectively closed on all 85 sides, except that in the front upper portion, there is formed a partially conical chute 2 to guide the bananas to be gathered into the box and one side 3 of the box is utilized as a door, being provided with hinges 4 on one side and a latch 5 on the other side to hold 90 the door closed and facilitate the opening of the door when desired.

The box 1 is supported on the upper end by a pole 6^a to elevate the box to the desired height.

Attached to and projecting from the pole 6^a is a bracket 7^a, comprising a pair of arms 7 secured at their inner ends to the pole 6^a and merging at their outer ends and formed to provide the curved extremity 8 dropping 100 to a point just above and in advance of the chute 2.

At the extremity of the curved end 8 of the bracket 7^a, there is secured a knife blade 9 of substantial length and extending transversely of the bracket and so positioned that when engaging the stem of a banana and on moving the box 1 downwardly, it may be directed to engage the fastening stem of a banana, indicated at 10^a, in Fig. 1, and by 110 a quick movement of the box cause the severance of the stem of the banana from the

bunch of bananas, so that the severed banana will drop into the chute 2 and gravitate into the interior of the box.

Enclosed within the box or container 1 is 5 a sack 10, which may be an ordinary paper sack used for enclosing bananas or other articles to be delivered to a customer.

The height of the paper sack is about equal to the level of the bottom of the chute 10 2 and the pole 6^a is made fast to the container 1 by means of bolts 11^a or otherwise.

The manipulating tool comprises a curved stem provided at one end with a handle 12 by means of which the clerk selling the bananas may engage the stem 13 of the bunch of bananas and so move it in one direction or the other to present the bananas to the chute 2 for directing them into said chute and causing the severance of the individual bananas from the bunch thereof at the will 20 of the clerk selling the bananas.

In preparing the bunch of bananas for separating the individual bananas therefrom, the bunch is hung up at a suitable 25 height by means of a string 14 and the manipulating hook 11 is forced into the stem of the bunch of bananas near the lower end thereof, so that the bunch of bananas is readily manipulated in one direction or the 30 other, as indicated in Fig. 1.

The invention is advantageous in eliminating all danger to the person handling the bananas, in that the fruit, on being severed from the stem or stalk, falls into a bag or 35 sack which thereby avoids direct handling of said fruit and thereby also avoids contact with scorpions or tarantulas sometimes found hiding in the bunch of bananas. The

bites of such insects are painful, and sometimes dangerous to those handling the bananas and such danger is therefore prevented. 40

What is claimed is:-

1. In a fruit-gathering device of the character set forth, a fruit receiving receptacle, supporting means therefor, a chute integral with said receptacle and adapted to selectively engage fruit to be severed and delivered into said receptacle, a bracket carried by and extending from said supporting means above said receptacle, and a depending cutting blade integral with said bracket and supported above and coacting with said chute for severing fruit selected thereby, said cutting blade extending transversely of 45 said bracket and directed downwardly toward and adjacent the forward edge of said chute. 55

2. A fruit gathering device of the character described comprising, a fruit receiving receptacle, a support therefor, a chute integral with said receptacle and adapted to selectively engage fruit to be severed and delivered into said receptacle, a bracket having two arms secured to said support above 60 the receptacle, said two arms merging at their ends remote from said support and formed to provide an arched extremity, and a downwardly directed cutting blade extending transversely of said arched extremity adjacent the forward edge of said chute and coacting therewith to sever selected fruit. 65

In testimony whereof, I affix my signature hereto.

JOHN STRAUB.
